UNITED STATES PATENT OFFICE.

JOHANNES VOPEL, OF BERLIN-MARIENDORF, GERMANY, ASSIGNOR TO C. LORENZ
AKTIENGESELLSCHAFT, OF BERLIN-TEMPELHOF, GERMANY.

MULTIPLEX ALTERNATING-CURRENT TELEGRAPHY.

Application filed September 15, 1924, Serial No. 737,786, and in Germany September 24, 1923.

My invention relates to improvements in multiplex telegraphy in which the synchronous transmission of several messages over one wire is effected by means of alternating currents of different frequencies. The system of multiplex telegraphy referred to acts by transmitting a plurality of altering currents of different frequencies and each carrying a different message over one transmission line from one terminal telegraph station to another associated station, while commutators are provided at this latter station connected between said transmission line and a plurality of terminal telegraph circuits each one of which corresponds to one of the above mentioned alternating telegraphing currents. The commutators operate in synchronism with each of their respective telegraphing currents in such a manner as to convert the received alternating currents into direct current telegraph impulses. The range of alternating current frequencies to be used for multiplex telegraphy depends essentially on the quality of the wire used. The number of messages to be transmitted for a certain range of frequencies depends on the selectivity of the receiving apparatus to be employed and on the telegraphing speed. According to my invention in a system of multiplex telegraphy of the kind referred to there are employed two alternating currents of the same frequency but with a phase difference of 90° for the simultaneous transmission of two different messages, whereby the number of messages to be transmitted for a certain range of frequencies may be doubled. Hence for simultaneously transmitting two telegrams two different frequencies are not required as heretofore, but only two alternating currents of the same frequency but having a phase displacement with respect to one another of 90° . If on the transmitting side there is therefore employed an alternator suitably constructed or connected for this purpose, the two alternating currents displaced by 90° can be separated by two commutators at the receiving station so arranged as to have a relative phase displacement with respect to one another of 90° , or by one single commutator having two sets of brushes displaced by 90° with respect to one another.

In multiplex systems of similar type to that previously referred to but using reso-

nating circuits for separating the different frequencies, telegraphic signs can only be transmitted by switching in or interrupting the alternating current, while according to a further feature of my invention when using synchronously operated commutators in the known manner hereinbefore mentioned separable current can be used, for instance in such a way that at the end of every telegraphic sign the phase of the alternating current is changed by 180° , which acts on the relay behind the commutator of the receiving system as a current opposite to the current of the signs, thus enabling a neutral relay to be employed. This reversal of the current by 180° can be attained by simply changing the polarity of the terminals of the line with the position of the key, or by employing a potentiometer across the terminals of the current generator, one pole of the transmission line being connected to a tapping point in the center of the potentiometer so that when operating the key either the one or the other terminal of the potentiometer is connected to the other pole of the line, or a repeater having a transformer ratio of 1:1 may be employed the primary or secondary of which is alternatively connected to the line according to the position of the key.

In order that the invention may be clearly understood and readily carried into effect the same will now be described more fully with reference to the accompanying drawings in which:

Figure 1 illustrates diagrammatically the electrical connections of the system of telegraphy referred to, and Figures 2 and 3 are curves representing the transmitted and commutated currents obtained in the various methods of operation according to the present invention.

Referring to Figure 1, T_1 , T_2 and T_3 are keys each of which is connected to one of three sources of alternating current of different frequencies and by means of which the first, second and third frequencies F_1 , F_2 , F_3 respectively can be tapped and transmitted along the line wire L by the common coupling relay A . For separating the carrying frequencies, there are provided rotating commutators K_1 , K_2 , K_3 coupled to the main line at A^1 in a similar way as the generators at the transmitting station. Each commutator is constructed so as to

commutate the alternating current of one particular frequency, so that the commutator K_1 commutes the frequency F^1 but does not commutate the frequencies F_2 and F_3 . The relay device R_1 is therefore actuated only by its own corresponding carrying frequency F_1 . The commutators K_2 and K_3 and their respective relay devices R_2 and R_3 are each operated in a like manner. The receiving commutators K_1 , K_2 and K_3 may be driven by one motor for instance, acting synchronously and in phase with a multi-wave alternator of the sending system producing the different signalling frequencies.

15 Referring to Figure 2 curve *a* shows the current sent along the wire when the sign is given and curve *c* the resulting commutated current in the receiving system. Curve *b* shows how during a spacing interval the phase of the alternating current sent along the wire is displaced by 180° as previously stated and curve *d* shows how at the same time the commutated current of the receiver changes its direction. Figure 3 illustrates the method of operation employing two currents of the same frequency but displaced with respect one to another by 90° ; f^1 is the alternating current sent along the wire, f^2 the same current commutated by a commutator in phase, f^3 the current commutated by a commutator displaced in phase by 90° . The resulting direct current of every half period being zero, f^3 does not act upon the receiving device.

16 What I claim and desire to secure by Letters Patent of the United States is as follows:

1. In a system for simultaneously transmitting several messages over one connecting line by means of two alternating currents of equal frequency and phase displacement of 90° with respect to each other and for separating these currents in the receiving station, the combination of a mechanical commutating device in the receiving system for each signaling current transmitted and means to operate said commutating devices synchronously and in like phase relationship with the transmitter at the sending system generating the respective signaling currents, said commutating devices being so arranged as to commute only their own particular signaling current.
2. In a system for transmitting simultaneously several messages over one connecting line by means of pairs of alternating currents of equal frequency and phase displacement of 90° with respect to each other, each pair being of a different frequency, and for separating these currents in the receiving system, the combination of a mechanical

commutating device in the receiving system for each signaling current transmitted and means to operate said commutating devices synchronously and in like phase relationship 65 with the transmitter at the sending system generating the respective signaling currents, said commutating devices being so arranged as to commute only their own particular signaling current.

3. In a system for simultaneously transmitting several messages over one connecting line, the combination of a number of generators at the sending system for producing pairs of signaling alternating currents, each two currents of each of said pairs being of equal frequency and displacement by 90° with respect to each other, a transmission line connecting said sending generators with a receiving system, mechanical 80 commutators at said receiving system, and means to operate said commutators in synchronism and in like relationship with one of said generators at said sending system, said commutators being arranged to commute only their own particular signaling current.

4. In a system as claimed in claim 1, in which in the pauses of signs alternating current with phase displaced by 180° is sent by 90 the transmitting system over the conducting wire and a current opposite to that produced by the signs is generated in the receiving system behind the commutator, two different messages being simultaneously 95 transmitted by the employment of two alternating currents of the same frequency, but with a phase difference of 90° , the two commutators in the receiving system having a relative phase displacement with respect to 100 one another of 90° so as to separate the two alternating currents differing in phase by 90° sent out by the transmitter.

5. In a system as claimed in claim 2, in which in the pauses of signs alternating current with phase displaced by 180° is sent by 105 the transmitting system over the conducting wire and a current opposite to that produced by the signs is generated in the receiving system behind the commutator, two different 110 messages being simultaneously transmitted by the employment of two alternating currents of the same frequency, but with a phase difference of 90° , the two commutators in the receiving system having a relative phase 115 displacement with respect to one another of 90° so as to separate the two alternating currents differing in phase by 90° sent out by the transmitter.

In testimony whereby I have affixed my 120 signature.

JOHANNES VOPEL.
